(57) **CLAIM**

The ornamental design for a compact, as shown and described.

DESCRIPTION

FIG. 1 is a perspective view of a compact showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a cross-sectional view following the direction of the arrow 8—8 in FIG. 6; and,

FIG. 9 is a perspective view of the compact according to our new design in a state in which an inner portion of the compact is pulled out from its original position.

The surface(s) or portion(s) of the article not shown in the drawing or described in the specification form(s) no part of the claimed design.
